WILLIAM R. WARD, OF SHARON, PENNSYLVANIA, ASSIGNOR TO WESTINGHOUSE ELECTRIC & MANUFACTURING COMPANY, A CORPORATION OF PENNSYLVANIA

CABLE CONNECTER

Application filed April 11, 1929. Serial No. 354,268.

My invention relates to electric conductors and particularly to means for preventing capillary action and the resulting siphoning of oil along said conductors.

It is common practice to operate electrical apparatus of certain types such, for example, as transformers, immersed in oil which acts as an insulating and cooling medium. When conductors for connecting transformer windings with outside circuits are provided with insulating coverings and the coverings extend below the oil level, the oil tends to travel along said conductors through the insulating covering by capillary action. If stranded cables are used, the oil also tends to travel along the conductor through the interstices between the strands of wire.

This action is undesirable, especially when the conductor leading from the casing is bent and extends downwardly below the level of the oil, since when oil, travelling along the cable, reaches a point below the level of the oil within the casing, a siphoning action occurs which, when once started, becomes continuous. This action results in loss of oil and necessitates frequent attention to replace it, thus increasing the expense of operation of the apparatus. The outside of the casing also becomes oily, collects dirt and presents an unsightly appearance.

An object of my invention is to provide anti-siphon connections for cable conductors that shall be fluid tight and thus, prevent fluid from travelling along such conductors.

Another object of my invention is to provide a conductor for fluid-insulated electrical apparatus that shall prevent the creepage of the fluid along the insulation of said conductor.

A better understanding of my invention will be obtained by reference to the accompanying drawing and to the following detailed description.

In the drawing, the single figure is a sectional view of a casing and cable connection illustrating my invention.

Referring to the drawing, a casing 1 is illustrated as containing an electrical device 2, such as a transformer, and a body 3 of

insulating fluid, such as oil. The transformer is connected to an external circuit, not shown, by stranded cable conductors 4, one of which is illustrated. The cable 4 extends out of the transformer casing 1, through a bushing 5, in which a tight joint is formed by the use of cement 6, or other adhesive substance, which aids in holding the conductor in place.

In order to form a solid smooth surface at the point where the lead passes the oil level, the end section 7 of the cable conductor 4, is stripped of its insulating covering, the bare section extending from the end of the cable to a point well above the oil level. A metal tube 9 is placed over the bare section of the conductor which is inserted in the end of a pressed tube terminal 10. The lower portion of the tube 9 and the terminal 10, after the end 7 of the conductor is inserted therein, are dipped in solder to form a fluid-tight joint at 12. The upper part of the tube 9 and the adjacent portion of the insulated cable are taped, as shown at 8, to prevent dirt or other deleterious substances from entering the tube. The terminal 10 is attached to a terminal board 13 where the leads 14 are brought from the windings of the transformer 2.

It will be apparent that my invention can be applied under any circumstances where a conductor passes from oil or other liquid to a gaseous medium above, regardless of the character of the insulation of the conductor.

It will be evident from the foregoing description that the disclosed cable connection is fluid tight below the oil level, and will prevent the oil from travelling along the conductor or its insulation.

Since many modifications, within the spirit and scope of my invention, may occur to those skilled in the art, I do not wish to be limited otherwise than by the scope of the appended claims.

I claim as my invention:

1. In combination, electrical apparatus immersed in oil, a stranded electrical conductor connected thereto and extending above the level of the oil, and means for

preventing the passage of oil along said conductor comprising a tube terminal for receiving the end of the conductor and a fluid-tight covering extending from said terminal to a point above the oil level.

2. In combination, a stranded electrical conductor having a portion thereof immersed in fluid, means for preventing the passage of said fluid along said conductor,

10 said means comprising a terminal attached to one end of said conductor, an impervious member surrounding said conductor and extending above the level of the fluid, and means for attaching said member to the conductor at the terminal end thereof, whereby said member and said terminal are made integral with said conductor to form a fluid-tight joint.

20 3. In a stranded electrical conductor having the end thereof immersed in a fluid, means for preventing the passage of said fluid along said conductor, said means comprising a terminal attached to one end of said conductor, an impervious member surrounding said conductor and extending above the level of the fluid and means for attaching said member to the conductor at the terminal thereof, said attaching means comprising an impervious material adapted 30 to fill the space between the conductor, said member and said terminal, whereby said member and said terminal are made integral parts of said conductor and the joint is made fluid tight.

35 4. In a stranded electrical conductor provided with an insulating covering and having the end thereof immersed in a fluid, means for preventing the passage of said fluid along said conductor, said means consisting of a terminal attached to the immersed end of said conductor and an impervious member surrounding said conductor and extending above the level of the fluid, and means for attaching said member 40 to said conductor at the terminal thereof, whereby said member and said terminal are made integral parts of said conductor to form a fluid-tight joint.

50 5. In a stranded electrical conductor, means for preventing the passage of fluid substances along said conductor, said means comprising a terminal attached to one end of the conductor, an impervious casing surrounding said conductor, means for attaching said casing to said conductor and to said terminal consisting of solder to fill the space between the said conductor, the said casing and said terminal, whereby they are made integral and the joint is made fluid 55 tight.

60 6. In a stranded electrical conductor, means for preventing the passage of fluid substances along said conductor, said means comprising a terminal attached to one end of the conductor, an impervious casing sur-

rounding said conductor, means for attaching said casing to said conductor and said terminal consisting of solder for filling the space between the said conductor, the said casing and said terminal, whereby they are 70 made integral and the joint is made fluid tight and means for sealing the other end of the casing and the conductor to prevent foreign substances from entering said casing.

7. In a stranded electrical conductor, means for preventing the passage of fluid substances along said conductor, said means comprising a terminal attached to one end of the conductor, an impervious casing surrounding said conductor, means for attaching said casing to said conductor and said terminal, said attaching means consisting of solder to fill the space between the said conductor, the said casing and said terminal, 80 whereby they are made integral and the joint is made fluid tight, and means for sealing the other end of the tube and the conductor to prevent foreign substances from entering said tubing, said sealing means 85 consisting of a plurality of turns of tape.

In testimony whereof, I have hereunto subscribed my name this 28th day of March 1929.
